UNITED STATES PATENT OFFICE

WILLIAM R. PHILLIPS, OF CRAFTON, PENNSYLVANIA, ASSIGNOR, BY DIRECT AND MESNE ASSIGNMENTS, OF ONE-THIRD TO ALFRED D. PHILLIPS, OF CINCINNATI, OHIO, AND ONE-THIRD TO JAMES L. ADAMS, OF CORAOPOLIS, PENNSYLVANIA.

WINDOW.

1,062,794.

Specification of Letters Patent. Patented May 27, 1913.

Application filed October 20, 1911. Serial No. 655,762.

To all whom it may concern:

Be it known that I, WILLIAM R. PHILLIPS, a citizen of the United States, residing at Crafton, in the county of Allegheny and 5 State of Pennsylvania, have invented new and useful Improvements in Windows, of which the following is a specification.

My invention relates generally to windows but was designed more particularly for 10 use in store front construction.

The principal objects of this construction are to provide an improved metal frame or sash which consists of but few simple parts, constructed to hold the glass firmly but 15 yieldingly, to permit a controlled ventilation, to drain to the outside any moisture that may run down the inner surface of the glass, to connect the parts together in a simple manner, and generally to cheapen the 20 manufacture of the frames and improve their efficiency.

Referring to the accompanying drawings, Figure 1 is a fragmentary view, partly in perspective and partly in cross-section showing the preferred form of my invention. Fig. 2 is cross-section on the line A—B, Fig. 1. Fig. 3 is a perspective view of one of the supports for the glass. Fig. 4 is a perspective view of the cork tiling shown in the 25 channel in Fig. 2. Fig. 5 is a perspective view of the ventilator shutter. Fig. 6 is a perspective view of the nut located in the said cork tiling, Fig. 1. Fig. 7 is a section of a modified form of my invention.

35 On the drawing, 1 designates the base member of my improved sash or window frame. It is composed of sheet metal having the flat base 2 which is intended to rest on or against the window sill or other fixed 40 structure to which the sash is to be secured. The outer edge of member 1 is bent upwardly to constitute the outer wall 3 which may have any desired cross-section. The member 1 is at the top of the wall 3 bent 45 toward the plate of glass 4 so as to form a gutter 5 adjacent to, and parallel with the glass. The extreme outer edge of the member 1 is bent upwardly to form the flange 6

which lies flat, against or parallel with, the outer face of the glass.

Beneath the glass 4 is a series of channels or U-shaped pieces 7 of sheet-metal having their flanges 8 and 9 extending upwardly and their bases or bottoms riveted or otherwise secured to the base of the member 1. 50 The channels and the member 1 are secured to the window sill or other support 10 by the screws 11 (only one shown). On the bottom of each of the channels 7 I place a short piece of cork tile 12 having its sides engaging 55 the sides of the corresponding channel.

A rectangular hole extends transversely through the flange 9 and the tile 12, and contains the correspondingly shaped elongated nut 13 which extends from the inner face of 60 the flange 8 into or through the flange 9. The screw 14 extends through the wall 3 and a hole in the flange 8 and works in the adjacent end of the nut 13 to hold the flange 6 in contact with the glass 4. The hole in 65 the flange 8 is preferably the size of the screw 14 but the shape and size of the hole is immaterial so long as it will not permit the nut to pass therethrough. This feature is not essential but is preferable so that, the 70 screw and the nut may be put in their places at the factory without danger of their becoming loose, misplaced, or lost. The upper edge of each tile 12 may be beveled to the thickness of the glass which is supported 75 thereby.

The outer edge of the member 1 is bent upwardly and backwardly to form the wall 15, having a downwardly turned terminal flange 16 a short distance beyond the channels 7.

17 is the generally U-shaped cover member made of sheet metal. It closes the space between the flange 16 and the outer face of the glass. It has the outer central base portion 18, carrying the lower flange 19 and the upper flange 20. The lower flange 19 first bends up slightly over a corresponding ridge 21 at the top of the flange 16 so as to prevent the entrance of water. From this 95 bend the flange 19 extends downwardly and

inwardly into engagement with the channels 7, which act as a fulcrum for the cover member when the upper flange 20 is drawn toward the glass 4 by the action of the 5 screws 14 which extend through the base portion 18 of the cover 17 into the outer ends of the nuts 13. The flange 20 has a terminal flange 23 bent up so as to engage the outer face of the glass opposite the 10 flange 6.

Within the space bounded by the wall 15, the flange 16 and that portion of the base 2 which lies under the wall 15 is the longitudinally sliding shutter 24 having an inner vertical flange 25 resting on the base 2 and an outer flange or curve 26 resting on the base 2 at its junction with the wall 15. The flange has the notches 27 at the bottom of the flange 25, and the notches 28 at the 20 bottom of the flange 26, the latter notches being arranged to register with corresponding notches 29 (only one shown) in the bottom of the wall 15. The shutter 24 is provided with a hole 30 in which a tool or handle may be placed for operating the same, an elongated hole 31 being provided in the wall 15 for the reciprocation of the tool or handle.

The lower edge of the flange 19 is provided with holes 32. The bottom of the gutter 5 is provided with holes through which moisture, condensed on the glass and collected in the gutter, may run down into the sash. The moisture flows through the 35 notches 32 and 27 and thence through the notches 28 and 29 when registering with each other. Air may flow in the reverse direction for ventilation, as may be readily understood. The openings 29 may be entirely open, partly open, or entirely closed by the proper adjustment of the shutter 24.

I do not limit my invention to the purposes specified nor do I limit my invention to the details and combinations described 45 and shown except so far as the claims will permit no other details and combinations.

In Fig. 7, I use a single screw 33 which extends through the cover member 17 and the wall 3 and into the wooden piece 34 to 50 bind the parts together.

I claim—

1. In a glass window, a sheet metal base having a lateral member in engagement with one side of the glass and a second lateral member located at the opposite side of the glass and bent upwardly and toward the first lateral member and then downwardly, a cover member having one portion in engagement with the remaining face of 60 the glass and another portion resting upon the said second lateral member, and means for clamping the glass between the said first member and the cover member.

2. In a glass window, a sheet metal mem-

ber having a flange in engagement with one face of the glass, a second sheet-metal member at the opposite side of the glass having a portion parallel with the glass and spaced therefrom, a third sheet-metal member having one edge in engagement with the opposite side of the glass, a central portion covering the space between the glass and the said parallel portion of the second member, and another edge extending beyond the said parallel portion, means for 75 clamping the glass between the first and third members, and means for supporting the glass and preventing the second edge of the third member moving toward the first member under the action of the clamping 80 means.

3. In a glass window, a sheet metal member having a flange in engagement with one face of the glass, a second sheet-metal member at the opposite side of the glass 85 having a portion parallel with the glass and spaced therefrom, a third sheet-metal member having one edge in engagement with the opposite side of the glass, a central portion covering the space between the glass 90 and the said parallel portion of the second member, and another edge extending beyond the said parallel portion, means for clamping the glass between the first and third members, and means for preventing 95 the second edge of the third member moving toward the first member under the action of the clamping means.

4. In a glass window, a hollow sheet-metal sash having lateral portions with 100 edges at opposite sides of the glass, a sheet-metal channel beneath the glass, a support for the glass within the channel, a nut carried by the channel, and a screw extending through each of the said lateral portions of 105 the sash and into the opposite ends of the said nuts.

5. In a glass window, a hollow sheet-metal sash having lateral portions with edges at opposite sides of the glass, a support 110 for the glass, a nut non-rotarily held by the support, and screws extending through the said lateral portions of the sash and into the nut.

6. In a glass window, a hollow sheet-metal sash having lateral portions with edges at opposite sides of the glass, a sheet-metal channel beneath the glass, a support for the glass within the channel, a nut carried by the channel, means to prevent the longitudinal movement of the nut toward the outer side of the sash, and a screw extending through each of the said lateral portions of the sash and into the opposite ends of the said nuts.

7. In a window, a glass, a sheet-metal base member having a weather-exposed wall bent upwardly and backwardly toward the

glass and provided with an upward bend at its inner edge, a sheet-metal cover member having a corresponding bend fitting the first-named bend, and a flange portion engaging the outer face of the glass, and means for securing the cover member to the base member.

Signed at Pittsburgh, Pa., this 17th day of October, A. D. 1911.

WILLIAM R. PHILLIPS.
